UNITED STATES PATENT OFFICE.

JOHN M. STADEL, OF WILMINGTON, DELAWARE, ASSIGNOR OF ONE-HALF
TO JACOB C. LOWREY, OF WILMINGTON, DELAWARE.

ENGINE.

No. 857,842.

Specification of Letters Patent.

Patented June 25, 1907.

Application filed November 2, 1904. Serial No. 281,124.

To all whom it may concern:

Be it known that I, JOHN M. STADEL, a citizen of the United States of America, and a resident of Wilmington, in the county of New-
castle, State of Delaware, have invented cer-
tain new and useful Improvements in En-
gines, of which the following is a specifi-
cation.

My invention relates to engines and the ob-
ject of my invention is to construct an engine
operating on the vacuum principle. In the
course of experiments, I have observed the
great power that can be gotten from dropping
a few drops of gasolene or similar fluid into a
vessel closed at all but its upper end, igniting
this gasolene or fluid, and closing the vessel
just after the rapidly burning vapor drives
the air out of the vessel. This action pro-
duces a vacuum strong enough to make it ex-
tremely difficult to remove the cover from
the vessel. As I have stated it is the object
of my invention to provide an engine in
which this action may be carried out, and I
have devised such an engine, which is illus-
trated, in one of its many forms, in the ac-
companying drawings.

My invention therefore consists in a vacuum
engine, the preferable embodiment of which
will be hereinafter more particularly de-
scribed and then claimed at the end hereof.

In the drawings which accompany this
application which I wish it distinctly under-
stood are merely to illustrate one way of car-
rying out my invention: Figure 1 is a side
elevation of an engine operating on my prin-
ciple; parts being shown in section in order
that they may better be understood. Fig. 2
is a vertical central section of the same view-
ing the engine at right angles to that shown
in Fig. 1. Fig. 3 is a detail of one of the
cams. Fig. 4 is a sectional view of the piston
and connecting rod, with the cylinder shown
diagrammatically. Fig. 5 is a similar view
with the parts in a different position. Fig. 6
is a vertical central section of the piston and
its igniter. Figs. 7 and 8 are top plan views
of the piston and its igniter. Fig. 9 is a per-
spective view of the igniter detached.

Referring now to the details of the drawings
by numerals: 1 indicates the cylinder sup-
ported on a casting 3 which in turn rests upon
and is bolted to the base 5, all three of which
may be formed of any construction desired.
The cylinder 1 is of course jacketed as indi-

cated at 7 and the jacket is of course pro- 55
vided with the inlet 8 and outlet 9 for the
usual water connections.

Resting upon and firmly bolted to the base
5 are the bearings, one on each side, in which
the main shaft 12 finds its support. The 60
shaft is provided with the usual crank 13
near its center and its ends project through
the casting 3. At one end of the shaft 12
there are keyed the usual fly-wheel 14 and a
gear 15, and at the opposite end there is a 65
gear 17, for the purpose of transmitting
power to the shaft 19 carrying the pulley or
other driving means. This shaft 19 is sup-
ported in bearings 20 and 21, the first of
which is formed integral with the cylinder 1, 70
and the other forms the upper end of a stand-
ard 23 securely bolted to the base 5. The
shaft also is provided with a large gear 24,
which meshes with the gear 17 and receives
motion therefrom and transmits it to the pul-
ley 25, from which it may be transmitted by
means of a belt to any machine to be driven;
or as shown in Fig. 1, the shaft 19 is provided
with an eccentric 27 and rod 29 to operate
a pump 30 for purposes of pumping. It is 80
manifest that the pump may be omitted if
desired, as may also the pulley 25 as the
power may be transmitted direct from either
of the shafts 10 and 19, as occasion may re-
quire.

The main shaft 12 is of course operated
from the cylinder, and hence the cylinder is
provided with a piston, such as the trunk
piston shown at 32 in Fig. 2, a connecting rod
34 being employed to connect the piston and 90
crank 13; and while these parts may be of
any ordinary construction, I prefer the special
construction shown in Fig. 2, and which will
hereinafter be described in detail in describ-
ing the igniter.

To the upper end of the cylinder 1 is con-
nected the head 36, which may be bolted to
the cylinder in the manner common to en-
gines; but this head, instead of being solid as
ordinarily made, is formed with a large open- 100
ing 38 which forms a seat for a valve 40. The
stem 41 which is connected to this valve 40
finds its bearing in a tubular support 43,
which, in turn is supported by the yoke 44,
illustrated in Fig. 2, as being bolted to the 105
head of the cylinder by the same bolts which
secure the head in position. The valve 40
needs to be normally closed, and for this pur-

pose a spring 46 is employed which is located around the stem 41 and finds its bearings against the valve and the lower end of the tubular support 43. In order that this 5 valve may be opened when necessary for the purpose and in the manner hereinafter described, I connect the upper end of the valve stem with links 48, and these links are connected with the upper curved end 50 of a rod 10 52 which is vertically movable in guides 54 screwed to the side of the cylinder. At the lower end of this vertically movable rod 52 there is an arm 53 in which is journaled a roller 54 and this roller bears upon a cam 56 15 secured to and revolving with a cam-shaft 58. The shaft 58 is supported in bearings 60, and at one end is provided with gear 61 meshing with the gear 15 hereinbefore described as secured to and revolving with the main 20 shaft 12. It follows, therefore, that as the main shaft is rotated by the piston, the gear 15 imparts motion to the shaft 58 through the gear 61, and as the shaft 58 rotates, the cam 56 is also rotated, the effect of which is to 25 elevate the vertically movable rod 52 and, through the links 48 and the valve stem 41, lift the valve against the tension of the spring 26, so as to open the cylinder and admit a new supply of air to balance the pressure on opposite sides of the piston. As the cam shaft 30 continues to rotate, the cam again moves to the position shown in the drawings and permits the spring 46 to close the valve.

The fuel supply-valve is indicated by the 35 numeral 63, and this valve is also normally kept closed by a spring 64. To one side of the valve casing is connected the inlet pipe 65, and to the opposite side, the supply pipe 66 which passes into the cylinder and is preferably provided with a curved end 67, arranged to drop the fluid whenever the valve 63 is opened against the tension of its spring. The valve 63 is also provided with a stem 69 which projects out of its stuffing box 70. To 40 operate this stem 69 to move it upwardly to supply gasoline to the cylinder, I employ a valve operating rod 73 supported in bearings 74 connected to the cylinder. This rod is normally pressed downward by means of a spring 75 so as to keep its lower end 76 resting on a cam 77 secured to the same shaft 58 on which is secured the aforesaid cam 56. From this construction it follows that as the cam 77 rotates, the lower end 76 of the rod 73 45 is elevated until it reaches up and contacts with the stem 69, and then the further upward movement opens the valve and supplies the gasoline or other fluid. The cam is so shaped that at the proper moment, its highest portion passes from under the end 76 of the rod 73, and said rod therefore is caused, by its spring, to descend, and of course the spring 64 at the same time closes the valve 63 and shuts off the supply of fluid. In order 50 that the supply may be regulated, I employ

an adjustable head 78 which is screw-threaded onto the rod 73; and this head may be adjusted so as to be nearer to, or farther from the valve stem 69, and thus open the valve 63 to a greater or less extent, according to the 55 way the head 78 is adjusted.

It will be obvious that any fluid fed from the supply pipe 66 may be ignited by any desired form of igniter, but I much prefer the form shown in the drawings. In this form 75 the piston is formed with bosses 82 and 83 formed on opposite sides and in which bosses is supported a small spindle 84. Projecting through the piston is any form of igniter contact 85, and the companion or movable contact is indicated at 87 as projecting from a collar 88 fixed to the spindle 84. At the opposite end of the spindle 84 is secured a cam 89 by which the spindle may be moved, and from this cam projects a lug 90 which is 80 adapted to contact with a stop 91 projecting from the piston. A spring 92 is coiled around the spindle 84 and has one end 93 projecting into a recess in the piston while its other end 94 passes up into an opening in the collar 88; 90 this spring being for the purpose of normally holding the lug 90 against the stop 91. The construction so far described is such that when the movable contact 87 touches the fixed contact 85 a current from the usual 95 electric circuit is completed, and of course when the spring 92 separates the movable contact 87 from the fixed contact 85 the circuit is broken and the usual spark results.

It is of course necessary to provide some 100 means for rotating the spindle 84 in order to make and break the circuit at the proper moment, and I accomplish this by forming an arm 96 on the piston end of the connecting rod 34, and through this arm works a rod 98 105 on the end of which is a finger 99; the latter being held in its normal position by means of a coiled spring 100. The parts are so constructed that the finger 99 is arranged to co-operate with the cam 89 and move the same 110 with its spindle 84 and movable contact point 87, against the tension of the spring 92. During the movement of the piston, in order that the lower end of the connecting rod 34 115 may move around the crank 13, its upper end necessarily works on the rod 101, and as the lower end of the connecting rod 34 moves from one side of the engine to the other, the arm 96, with its finger 99, is caused to reciprocate back and forth in a line across the face 120 of the cam 89. In doing this, the finger 99 contacts with the projection 102 on the cam 89 and rotates said cam until the further movement of the arm 96 and its finger 99 125 frees the finger from the projection 102, and thus permits the spring 92 to return the cam to its normal position. The first half of the movement of the arm 96 and its finger 99 causes the contact 87 to close the circuit, and the positions of the parts are such that the 130

instant the crank passes the lower center, the finger 99 moves to the point where the cam is freed and thus permits the spring 92 to return the cam, thus separating the two contacts and making the spark. It will be noticed that the bearing 104 at the upper end of the connecting rod is provided with an oil aperture 105 so that, when this aperture 105 and a similar aperture 106 in the wall of the piston are moved so that they coincide with an opening 107 in the casing of the cylinder, the nozzle of an oil can may be inserted through these apertures and the bearing of the piston rod suitably oiled. In order that the spindle 84 may also be properly oiled, I form a depression or recess 110 in the upper face of the piston, and this depression is connected by means of passage 111, shown in dotted lines, with the aperture in which is located the spindle 84. It follows that when the piston moves up and down and is lubricated by the oil flowing from the lubricator 112, the oil is scraped in the depression or recess 110 and from thence flows through the passage 111 to the spindle and thus thoroughly oils the same.

The operation of my engine is as follows: As shown in Fig. 2, the parts are illustrated with the supply valve 63 closed and with the valve 40 also closed. This means that after the fluid has been supplied to the cylinder, it has been ignited and the resulting hot flame causes a swift rush of the air from the cylinder, and the valve 40 is then closed, thus creating a vacuum in the cylinder which causes the piston to be drawn upward. By the time the piston reaches the upper end of its stroke the valve 40 is opened, and hence the air may again enter the cylinder to balance the pressure on opposite sides of the piston, which latter is returned to its lower position by the weight of its parts and by the momentum of the fly wheel. As the piston reaches the lower end of this stroke, the connecting rod 34 moves so as to close the circuit between the contacts 85 and 87, and the cam 77 is moved so as to shove its rod 73 upward to open the supply valve and permit the fluid to drop on to the piston. At this point, a slight further movement permits the supply valve 63 to close and the movement of the crank past the lower center, in the manner before described, permits the movable contact 87 to move away from the contact 85, thus causing a spark which ignites the fluid, the resulting explosion or the flames resulting from the ignition, causing a rushing upward

of the gases, driving all the air out of the cylinder. The cam 56 is so shaped that just after the explosion takes place it permits the spring 46 to close the valve 40, thus forming a vacuum in the cylinder between the piston and head and, as the atmospheric pressure acts upon the opposite side of the piston, the latter is moved up, as before described. 65

What I claim as new is:

1. In an engine, a working piston, a cylinder therefor having a fuel supply and an exhaust port near one end, a valve for said fuel supply, an igniter arranged to ignite the fuel when the piston is near the opposite end, a valve controlling said exhaust port, means operating from the crank shaft for opening the valve supplying the fuel, and means for closing the exhaust valve immediately after 70 the ignition and expulsion of the gases, said valve afterward opening to permit the entrance of a new supply of air, substantially as described.

2. In an engine, a working piston, a cylinder therefor having a fuel supply and an exhaust port near one end, a valve for said fuel supply, an igniter arranged to ignite the fuel when the piston is near the opposite end, a valve controlling said exhaust port, means 80 operating from the crank shaft for opening the valve supplying the fuel, and means comprising a cam permitting the exhaust valve to close immediately after the ignition and expulsion of the gases, said cam afterward opening said exhaust valve to permit the entrance of a new supply of air, substantially 85 as described.

3. In an engine, a working piston and its piston rod, a cylinder therefor having a fuel supply and an exhaust port near one end, a valve for said fuel supply, an igniter arranged to ignite the fuel when the piston is near the opposite end, said igniter having its circuit made and broken by the movement of 95 the said piston rod, a valve controlling said exhaust port, and means operating from the crank shaft for opening the valve supplying the fuel and means for closing the exhaust valve immediately after the ignition and expulsion of the gases, said valve afterward 100 opening to permit the entrance of a new supply of air, substantially as described.

Signed by me at Wilmington, Del., this 29th day of October, 1904.

JOHN M. STADEL.
